DOOR CHECK

Stuart W. Parsons, New Britain, and George E. Gilpatrick, West Hartford, Conn., assignors to The Stanley Works, New Britain, Conn., a corporation of Connecticut

Application January 14, 1955, Serial No. 481,892

8 Claims. (Cl. 16—66)

The present invention relates to improvements in door checks of the type commonly used on screen and storm doors, generally in combination with door-closer means.

Door checks of the aforesaid type generally include a cylinder in which checking fluid is compressed by a piston during closing of the door and from which the fluid is allowed to escape through a restricted outlet or bleed passage at a rate such as to retard the door-closing movement to prevent slamming. The associated door closer generally includes a spring which is loaded by opening of the door and which provides the force necessary to close the door.

It has heretofore been a problem in the operation of such door checks to obtain a satisfactory adjustment of the rate of escape of the checking fluid from the cylinder such that the door will close without undue delay when opened wide, yet will not slam when opened a small amount. The difficulty arises from the fact that when the bleed passage is adjusted to have a sufficiently small flow rate to insure gentle closing of the door from a small angle of opening, door closing from a wide-open position is extremely slow and pressure in the checking cylinder may build up sufficiently to cause objectionable bouncing of the piston on the checking fluid, with accompanying oscillations of the door, which of course further delays the closing movement; and when the size of the bleed passage is increased sufficiently to permit the door to close from a wide-open position without bouncing of the piston or excessive delay, the door will not be checked enough when opened through only a small angle and will therefore slam. As a result, the adjustment of prior art devices of this type has generally been limited to a compromise between these extremes which is not entirely satisfactory for either.

One object of the present invention, therefore, is to provide in a door check of the character described means for automatically controlling the rate of escape of the checking fluid during door closing so as to prevent both door slamming and bouncing of the piston on the checking fluid.

Another object is to provide in such a door check improved flow regulating means for the checking fluid bleed passage which compensates automatically for differences in the amount of door opening or varying external forces applied to the door and enables the door to close quickly, yet gently, regardless of the angle through which it is opened or the external force applied to it.

Another object is to provide in a door check an improved flow regulating valve for the checking fluid bleed passage which automatically and continuously adjusts the bleed passage flow rate in accordance with the pressure developed in the checking fluid during door closing, and tends to equalize the door closing period for various angles of door opening.

Another object is to provide in a door check an improved checking fluid bleed valve of simple and inexpensive construction which automatically regulates flow rate in accordance with pressure developed in the check-

2

ing fluid, which is small in size, which requires no adjustment when once installed, and which is capable of operating dependably for long periods without care or attention of any kind.

5 Other objects will be in part obvious, and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawing:

Figure 1 is a vertical sectional view of a combination door check and door closer having a bleed passage flow control valve constructed in accordance with the present invention; and

15 Figure 2 is a fragmentary sectional view of a portion of the door check of Figure 1, illustrating the manner of operation of the flow control valve during closing of the door.

20 Referring to the drawing, the invention is illustrated in connection with a combination door check and door closer including a checking cylinder 2 adapted to contain checking fluid, which in the instant embodiment is air, a piston 4 in the cylinder mounted on a piston rod 6, and a door-closing spring 8. The spring 8 illustrated is of the torsion type and is shown enclosed within the door check, but it should be understood that the spring may be of any desired type and may be mounted in any desired manner, the invention being in no sense limited to the type of door closer or mounting arrangement employed.

25 The check is adapted to be secured to a door frame header by a mounting plate 10. Depending from the plate 10 is an elongate screw 20 supporting a cover 18 on which is rotatably mounted a concentric barrel-shaped knuckle or housing 16. The housing is open at its top and has a horizontally extending boss 32 formed with a cylindrical recess 30 in which one end of the checking cylinder 2 is secured. The piston rod 6 extends through a cap 34 at the other end of the cylinder and is pivotally connected by pin 14 to a bracket 12 which is adapted to be fastened to a door.

30 Surrounding the screw 20 is a sleeve 22 of square cross section which is secured at its lower end to the cover 18 and has fixed at its upper end a ratchet wheel 24 engageable with a pawl 26 on the mounting plate. The spring 8 is enclosed within the housing 16, being hooked thereto at its upper end and secured at its lower end to a disc 28 which is slidably, but non-rotatably, mounted on the square sleeve 22. With this arrangement the spring may be adjusted to provide any desired amount of initial door-closing bias by merely rotating the cover 18, sleeve 22 and ratchet wheel 24 relative to the housing, so as to wind up the spring the necessary amount. The bottom of the cover is diametrically grooved as at 29 to permit insertion of a bar or the like, facilitating rotation of the cover to wind up the spring.

35 The piston 4 includes a cup-shaped flexible packing 36 clamped between a washer 38 and a backing plate 40, and mounted on the piston rod 6 by nuts 42. The outlet bleed passage through which the air compressed in the cylinder by the piston is allowed to escape includes a bore 50 in the wall of the housing 16 at the bottom 45 of recess 30. With this arrangement opening of the door moves the piston to the right and admits to the left of the piston a charge of air proportional to the piston displacement. The door opening movement also swings the cylinder and rotates housing 16 about its axis, thereby increasing the loading on spring 8 so as to provide the necessary force to close the door. When the door is released, the spring 8 rotates the housing back to its

initial position and, as the door closes, the movement of the piston in a left-hand direction compresses the air in the cylinder and checks the door closing movement in accordance with the rate of escape of air through outlet bore 50.

In accordance with the invention, the rate of escape of checking fluid from the cylinder is controlled by a flow regulating valve which is automatically and continuously adjusts the flow of air through the outlet bleed passage in accordance with the pressure developed in the checking cylinder. The valve consists of a wafer or disc 52 of elastic material which is dished on one side to form a central portion 53 whose thickness progressively decreases towards its center. At the center of portion 53 the valve has an extremely small hole 54, which of necessity has been greatly magnified in the drawing, but which in reality is scarcely visible to the naked eye, being of the order of only a few thousandths of an inch in diameter. The material for the valve may be any suitable elastomer such as, for example, neoprene.

The valve is disposed within the end of the cylinder formed by recess 30 so as to cover bore 50, and its peripheral portion is firmly clamped against the radial shoulder 55 of the recess by a washer 56 which may be integral with the cylinder 2. The dished side of the valve faces the piston 4 and behind the central portion 53 of the valve the wall of the housing is relieved to provide a shallow pocket 58 forming a concave surface surrounding the inner end of bore 50.

In the operation of the door check with the valve 52, as the piston 4 moves to the right during door opening some air flows into the cylinder through opening 54 and augments the flow of air past packing 36 in forming the air charge on the left side of the piston. During the door closing movement air is compressed in the cylinder and is expelled through the central opening 54 in the valve and through outlet bore 50. Since the opening 54 is quite small, for small angles of door opening the valve will effectively throttle the escape of air from the cylinder and insure gentle closing of the door without slamming. As the door is opened wider, however, increasing the return force of the spring 8 and correspondingly increasing the air pressure in the cylinder 2, the thin central portion 53 of the valve is automatically ballooned out or distended into the pocket 58 by the increased air pressure, as shown in Figure 2, and the opening 54 is thereby expanded and automatically increases the rate of air escape from the cylinder. The valve thus automatically provides an increased air discharge rate when it is needed to dispel the larger air charge formed behind the piston when the door is opened wide, and thereby prevents excessive pressure build-up which might cause bouncing of the piston on the air charge or otherwise excessively delay the door closing. Hence the valve tends to equalize the door closing period for all angles of door opening. Since the valve is sensitive to checking fluid pressure, it also compensates automatically for the application of external forces such as wind force on the door, increasing the air escape rate as necessary to prevent piston bouncing and provide smooth door closing without slamming under all circumstances. As the door closing movement continues and the pressure in the cylinder tends to fall, the elastic valve will automatically distend to a lesser degree and the size of the hole 54 will be reduced accordingly, so that the door will not speed up and slam, but will continue to close gently until it latches.

The mounting arrangement and shape of the valve as above described provide many advantages which contribute to improved door operation and long valve life. The firm clamping of the peripheral portion of the valve between shoulder 55 and washer 56 prevents air leakage around the valve as well as preventing the peripheral portion of the valve from being pulled radially

out of position when the central portion is distended. The progressively decreasing thickness of the dished central portion 53 of the valve provides a cantilever action when the valve distends which enables the thickness of the valve at opening 54 to be a minimum, and thus permits opening 54 to vary in size with maximum sensitivity to air pressure in the cylinder while avoiding stretching of the valve out of shape during operation. The bottom surface of the pocket 58 provides a stop limiting outward bulging of central portion 53, and thereby preventing rupture of the valve or stretching beyond its elastic limit as well as limiting the maximum size of opening 54 so that wind or other external forces on the door cannot cause it to slam.

Thus it may be seen that the valve compensates automatically for differences in the air pressure developed in the cylinder, thereby regulating operation of the door check automatically in response to different amounts of door openings or various external forces on the door so as to prevent both slamming of the door and undue delay in closing of the door. When once installed, the valve requires no further adjustments of any kind, but will operate automatically to regulate the pressure in the cylinder as required to provide smooth and substantially uniform door closing regardless of the angle at which the door is opened. The valve is simple and inexpensive in construction, as well as small in size and, since the particular shape and mounting arrangement of the valve protects it against acquiring a permanent set, the valve 30 will operate dependably for long periods without care or attention of any kind.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

We claim:

1. In a door check having a cylinder and a piston mounted for reciprocation in the cylinder responsive to door movement and adapted to pressurize checking fluid in the cylinder to retard closing of the door, means forming an escape for fluid pressurized in the cylinder comprising a valve including an elastic wafer having a distensible portion with a minute aperture therein providing the sole passage through said valve through which checking fluid pressurized in the cylinder may escape and mounting means for the wafer forming an open pocket on the side of the wafer opposite from the piston and dimensioned to permit the wafer to distend and vary the size of the said valve aperture responsive to fluid pressure thereon, whereby variations in the closing force on the door are automatically compensated for by distension of said distensible portion and resultant expansion of said aperture in accordance with the pressure of said checking fluid.

2. In a door check having a cylinder and a piston mounted for reciprocation in the cylinder responsive to door movement and adapted to pressurize checking fluid in the cylinder to retard closing of the door, escape means for fluid pressurized in the cylinder comprising a valve including an elastic wafer having a central distensible portion, said central portion having a thickness progressively diminishing toward its center and having a minute aperture at its center.

3. In a door check having a cylinder and a piston mounted for reciprocation in the cylinder responsive to door movement and adapted to pressurize checking fluid in the cylinder to retard closing of the door, means form-

ing an outlet passage to permit the escape of fluid pressurized in the cylinder, means for regulating flow of fluid through said outlet passage comprising an elastic wafer having a central outwardly distensible portion covering the outlet passage and provided with a minute aperture at its center providing the sole passage for checking fluid from said cylinder to said outlet passage, and a surface surrounding the outlet passage and outwardly spaced from said distensible portion to provide a stop limiting outward movement of said distensible portion.

4. In a door check having a cylinder, a piston mounted for reciprocation in the cylinder responsive to door movement and adapted to pressurize checking fluid in the cylinder to retard closing of the door, means forming an outlet passage to permit the escape of fluid pressurized in the cylinder, means for regulating flow of fluid through said outlet passage comprising an elastic wafer having a central outwardly distensible portion closing the outlet passage, said central portion having a thickness progressively diminishing toward its center and having a minute aperture at its center, and a surface surrounding the outlet passage and outwardly spaced from said distensible portion to provide a stop limiting outward movement of said distensible portion.

5. In a door check having a cylinder, means providing an air outlet of fixed cross sectional area for the cylinder, a piston mounted for movement in the cylinder in one direction during door opening movement and in the other direction during door closing movement and arranged to compress air in the cylinder to check closing of the door, means for regulating flow of air through the outlet comprising a valve including an elastic disc having a centrally disposed distensible portion covering the outlet and having a minute central aperture providing the sole air flow passage through said valve, and means anchoring the peripheral portion of said disc in fixed relation with said outlet.

6. In a door check having a cylinder, a piston mounted for reciprocation in the cylinder responsive to door movement and arranged to compress air in the cylinder to check closing of the door, means providing an outlet passage of fixed diameter for said cylinder for releasing air compressed therein, means for regulating flow of air through the outlet passage comprising a valve including a disc of elastic material having a peripheral portion secured to the cylinder and having a central outwardly distensible portion closing the outlet passage, said central portion having a thickness progressively diminishing toward its center and having a minute aperture at its center, and a surface surrounding the outlet passage in outwardly spaced relation to said distensible portion and with which said distensible portion may engage when distended to limit distension thereof to less than the elastic limit of said elastic material.

7. In a door check having a cylinder containing checking fluid, a reciprocable piston in the cylinder attachable to a door for movement in one direction responsive to opening of the door and in the other direction responsive to closing of the door, and means forming a wall closing one end of the cylinder between which and said piston fluid is pressurized in the cylinder during door closing movement, said wall having an outlet of fixed cross sectional area for releasing fluid pressurized in the cylinder, means for regulating flow of fluid through the outlet in accordance with fluid pressure in the cylinder comprising a plate of elastic material having a distensible thin portion surrounded by a peripheral portion, a holder securing said peripheral portion to said wall to prevent fluid flow past said peripheral portion with said distensible thin portion covering said outlet and exposed on its inner side to the pressure in said cylinder, said distensible thin portion having a minute aperture at its center and being arranged to balloon outwardly to expand said aperture in accordance with the pressure in said checking fluid, and a relieved portion at the inner end of said outlet forming a concave surface facing the outer side of said plate toward which said distensible thin portion may distend.

8. Automatic means for regulating door closing speed in a door check of the type having a cylinder containing checking fluid, a piston reciprocable in the cylinder responsive to door movement and arranged to compress checking fluid therein during closing of the door to retard door closing movement, means providing an enclosing wall for the cylinder having an outlet passage of fixed diameter through which fluid pressurized in the cylinder may escape, said regulating means comprising an enlarged portion at the inner end of said outlet passage forming an inwardly facing pocket in said wall surrounded by a radial shoulder, a disc of elastic material having a peripheral portion clamped against said shoulder and having a central portion covering said pocket and outwardly distensible thereto responsive to pressure in said cylinder, said central portion being dished on its inner side and having a minute perforation at its center variable in size responsive to distension of said central portion of the disc.
